UNITED STATES PATENT OFFICE.

RENÉ JULES DUPUY, OF PARIS, FRANCE, ASSIGNOR TO COMPAGNIE GÉNÉRALE
D'ÉLECTRICITÉ, OF PARIS, FRANCE, A CORPORATION OF FRANCE.

APPARATUS FOR PROTECTING STEAM-TURBINES AGAINST RUST.

1,282,680.

Specification of Letters Patent. Patented Oct. 22, 1918.

Application filed September 12, 1917. Serial No. 190,958.

To all whom it may concern:

Be it known that I, RENÉ JULES DUPUY, of 7 Rue d'Alleray, at Paris, Department of the Seine, France, citizen of the French

Republic, have invented certain new and useful Improvements in Apparatus for Protecting Steam-Turbines Against Rust; and I do hereby declare the following to be a full, clear, and exact description of the invention, such as will enable others skilled in the art to which it appertains to make and use the same.

The present invention relates to steam turbines and has for its object to protect the fixed and moving blades, disks and other parts against rust due to the presence of moisture which remains in or gains access to the interior of the turbine during the time when it is stopped.

The invention consists in applying to the turbine a blower which, during the operation of the turbine, is cut off by a valve which is opened at the time of stopping so as to cause the turbine to be traversed by a current of dry air which takes up the remaining particles of water and maintains in the interior of the machine a dry atmosphere, thereby avoiding rust. The air blown in can be heated by means of a heating device interposed immediately after the blower.

The accompanying drawings show by way of example different arrangements of apparatus forming the object of the invention.

Figure 1 is a diagrammatic elevation partly sectional of a turbine provided with a ventilating device.

Fig. 2 is a similar diagrammatic elevation of a modification.

The turbine is shown at T, T¹ designates the admission pipe in which is interposed a valve A serving to control the steam. A valve B permits the interior of the turbine (admission end) to be placed in communication with the atmosphere. At the opposite end of the turbine is located a blower V separated from the turbine by a valve C. A device R applied to the conduit for the air from the blower V serves to heat the air, so that a current of dry air is constantly obtained. During the times when the turbine

T is stopped the valve A of the admission pipe T¹ is closed and the valve B is opened, so that the interior of the turbine is put into communication with the atmosphere; the blower is then operated to deliver air into the turbine. A current of air which is dry or, in any case, it is not saturated, thereby traverses the whole of the turbine, takes up the particles of water remaining and maintains in the interior of the machine an atmosphere sufficiently dry to avoid rust of the oxidizable metallic parts.

The heating device shown in Fig. 1 is constituted by a resistance D through which an electric current passes.

Fig. 2 shows a modification in which the blower V and its accessory apparatus are mounted on the exhaust pipe G. In this example the heating apparatus shown at S is formed of a jacketed tube within the outer envelop of which a current of steam arriving by the tube E is caused to circulate, tube F serving for the escape of the condensed water.

It is well understood that modifications can be made in the invention and the blowing apparatus mounted either on the body of the turbine T or on the condenser itself, or on another part in communication with the exhaust.

I claim:

1. A steam turbine including a valve in the steam inlet pipe adapted to establish communication between the interior of the turbine and the atmosphere, and means for blowing air through the turbine and out of said valve.

2. A steam turbine including a valve in the steam inlet pipe adapted to establish communication between the interior of the turbine and the atmosphere, means for blowing air through the turbine and out of the valve, and means for controlling the flow of said air.

3. A steam turbine including a valve on one side of the rotor adapted to establish communication between the interior of the turbine and the atmosphere, and means on the opposite side of the rotor for blowing air through the turbine and out of said valve.

4. A steam turbine including a valve on

one side of the rotor adapted to establish communication between the interior of the turbine and the atmosphere, means on the opposite side of the rotor for blowing air 5 through the turbine and out of said valve, and means for heating the air as it passes from the blower to the turbine.

In testimony whereof I affix my signature, in presence of two witnesses.

RENÉ JULES DUPUY. [L. S.]

Witnesses:

JOSEPH GEMENIE,
D. H. LAWSON.
